LEAF HOLDER FOR BOOKS, PAMPHLETS, &c.

No. 369,217.

Patented Aug. 30, 1887.

UNITED STATES PATENT OFFICE.

SIDNEY C. THOMPSON, OF BROOKLYN, NEW YORK.

LEAF-HOLDER FOR BOOKS, PAMPHLETS, &c.

SPECIFICATION forming part of Letters Patent No. 369,217, dated August 30, 1887.

Application filed December 8, 1886. Serial No. 220,934. (No model.)

To all whom it may concern:

Be it known that I, SIDNEY C. THOMPSON, a citizen of the United States of America, and a resident of Brooklyn, in the county of Kings 5 and State of New York, have invented certain new and useful Improvements in Leaf-Holders for Books, Pamphlets, &c., of which the following is a specification.

This invention relates to that class of devices 10 which are used to confine the open leaves of a book flat and smooth in such open position and against accidental turning or displacement; and it consists in the combination, with a flat plate of suitable shape and adaptation to lie 15 behind or under certain of the leaves of the book on either or both sides of its binding portion, and provided with suitable rigid bearings, which are in the plate at a position outside of its bearing behind or under the leaves 20 of the book, of a rocking rod hung in said rigid bearings and adapted to extend and bear with suitable pressure upon the upper face of the opened leaves, which pressure is secured to the said rocking rod from the reaction of a suitable 25 spring applied in a proper relation to it, and said bearing-rod to be swung out of such contact when desired, all as will hereinafter appear, reference being had to the accompanying sheets of drawings, in which leaf-holding 30 devices embodying the present invention are carried out.

Figure 1 is a perspective view of an opened book with a leaf-holder constructed under the present invention applied to same, securing 35 the leaves open. Fig. 2 is a plan view of the leaf-holder shown in Fig. 1. Fig. 3 is a cross-section through an opened book with the leaf-holder applied thereto, the latter appearing in end elevation with certain parts in section. 40 Fig. 4 is a sectional view on line 4 4, and Fig. 5 is a detail sectional view on line 5 5. Fig. 6 is a plan view of a leaf-holder under the present invention, showing a modified form of construction. Fig. 7 is a section on line 7 7.

45 In the drawings, A represents a book consisting of a back or cover, B, and leaves C.

D is the leaf-holder, of which E is a flat supporting-plate, and F a yoke-shaped rod. The supporting-plate E is made with a body portion, a, and bifurcated portions b b, with a space, d, between such parts b b, and the body por-

tion a is to lie beyond or outside of the leaves of the book at the folding and bending part thereof. These parts b b are to be made of considerable length to give the desired bearing 55 and rigidity to the supporting-plate E. The plate E at its outer end is provided with vertical ear-pieces f f² opposite each other, and having holes g in them for bearings, in which the yoke-shaped rod F is hung for a rocking 60 movement. This rod is kept from longitudinal movement in and through the bearings by a collar, h, brazed or soldered to the rod outside of one of the bearings g, and by a pin, k, at the outside of the other of the bearings, which pin 65 passes through the thickness of the rod, as shown in Figs. 1, 2, and 3.

The yoke-shaped arm F, on either outer side of its bearings, continues in inward and downward extensions F², as shown, to a suitable 70 position of bearing upon the face of the leaves of the book, and the ends of the holding-arms are turned up or curved, as at l, whereby in their bearing on the leaves the same will not be torn or pierced. As seen in Sheet 1 of the 75 drawings, the portion of the yoke-rod F between its bearings g of the plate E is straight, and upon and around it is placed a coiled spring, G, one end, j, of which is fastened to the rod F, and the other end of which is fastened to the plate E, or ear-piece f thereof, in a 80 manner to exert its force upon the rod F to carry its arms downwardly to bear with suitable pressure upon the outer face of the leaves of the book when the device is in suitable position in relation to the book therefor, as shown in Figs. 1 and 3 of the drawings. The collar h of the rod F has a radial pin, m, and the ear-piece f² has a pin or abutment, n, so placed and distanced in relation to each other that the 85 rod F is allowed a suitable downward swing to exert the necessary pressure on the leaves of the book, as described, and yet when not in use the rod is prevented from an undue rotation under the reaction or unwinding of the 90 spring G. (See Fig. 4.)

The plate E, with the ear-pieces f f² thereof, is made in one piece of metal struck out in the form shown, and the parts f f² forming the ear-pieces turned up at right angles, as shown in 100 Figs. 1, 2, and 3.

The portion of the device between the ear-

pieces $f f^2$ embracing the coiled spring is preferably inclosed by a tubular casing, x , and, when constructed as above described, the device is practical, mechanical, cheap, neat, and effective and will not get out of order.

While a particular method of securing the spring-pressure has been shown and described, other means of securing such pressure may be employed—as, for instance, by providing the rod F with a crank or cam projection, p , which works against a plate-spring, q , secured or made part of the plate E , as illustrated in Sheet 2 of the drawings.

Having thus described my invention, what I claim, and desire to secure by Letters Patent, is—

1. The combination, with the bearing-plate E , shaped and adapted to lie behind and between the leaves of an opened book, pamphlet, &c., on either side of the binding or folding portion thereof, of a rod, F , hung in rigid bearings of a portion of the plate at a part thereof outside of its contact with said leaves, which rod has

a spiral spring coiled around it between such bearings, one end of which is fastened to the rod and the other to a part of the plate E , and having arms F^2 , all constructed and arranged for contact with the outer face of the uppermost leaves, substantially as described.

2. A leaf-holder for books, consisting of a plate, E , formed with the body part a and bifurcated parts $b b$, having bearings g formed in ear-pieces $f f^2$, which are stamped out in one piece with said plate and turned up, and a rod, F , hung in said bearings, to which is applied a spring-resistance, and having arms $F^2 F^2$, of suitable extent and shape, substantially as described, and for the purpose specified.

In testimony that I claim the foregoing as my invention I have signed my name, in presence of two witnesses, this 13th day of September, 1886.

SIDNEY C. THOMPSON.
